UNITED STATES PATENT OFFICE.

HENRY D'OLIER, JR., OF BRIDGEPORT, CONNECTICUT.

SUPPORTING CHAIN FOR ELECTRICAL CONDUCTORS.

Application filed December 29, 1925. Serial No. 78,161.

This invention relates to supporting chains, particularly adapted for the support of electrical conductors and for connector-sockets, such as those used in supporting incandescent electrical lamps, although I contemplate the use of the invention in any field for which it may be adapted by the nature of my improvements.

An important object of the invention is to provide such a supporting chain having a straight path for the electrical conductor or conductors in contradistinction to the conventional type of supporting chain in which the links are so formed that the conductor

10 must be threaded backward and forward through the links, which constitutes a source of inconvenience in assembling the electrical conductors with the chain and in removing the electrical conductors therefrom, when

15 such removal is desirable.

The improved chain, provided with such a straight path, makes it possible to run the conductor readily through the chain, or to remove it therefrom with equal facility, by

20 simply threading the conductor in the straight path along the axis of the chain, and when thus assembled the conductor is held in place by suitably bent portions of the links, so that the conductor cannot be dis-

25 placed accidentally from the chain, the whole presenting a neat, compact, and attractive appearance.

A further object of the invention is to provide such a chain in which each link is formed of a single piece of wire bent to form body portions extending along the axis of the conductor or chain, each link having its ends formed in such a way as to adapt the several links each to be connected with the adjacent link, and the middle portion of the wire being bent around in such a way as to wholly or partially embrace the conductor, this bent middle portion being also adapted for easy connection with the connecting parts of the

35 free ends of the adjacent link in making up the chain.

Still another object of the invention is to provide such a chain with terminal links adapted for connection respectively with a connector-socket to support the latter, or with any other suitable electrical device, and to adapt the chain for ready connection with a primary support.

Still another object of the invention is to

40 provide a terminal link which can be readily connected with such a connector-socket and

which may, if desired, be constituted an integral portion of said socket.

The above and other features of the invention are fully illustrated and described in the accompanying drawings and specification and are pointed out in the claims.

In the drawings:

Figure 1 is a view in elevation of a supporting chain for an electrical conductor, shown in combination with an electric lighting unit and with a primary support therefor, having electrical conductors illustrated in operative position therewith.

Fig. 2 is a fragmentary detailed view of a portion of the chain showing the connection between two of the links, this figure being taken from a view point at right angles to that shown in Fig. 1.

Fig. 3 is a fragmentary detailed view in longitudinal section of the terminal links showing the mode of connection with the socket.

Fig. 4 is a detailed view in transverse section on the line IV—IV of Fig. 1.

Fig. 5 is a view in perspective of one of the terminal links, isolated.

In the illustrated embodiment, the part designated by the reference numeral 1 is an electric lamp of the conventional type, shown in assembled relation with a socket 2 and surrounded by a globe 3 mounted in a holder 4 secured to the socket, these parts being of a conventional character in their general construction.

In pursuance of the invention, I have illustrated a chain having a straight path for an electrical conductor, or conductors, 5, adapted to supply the electrical current to the lamp, and extending through the chain to a receptacle 6 mounted upon an outlet 7 forming part of a conduit system 8 which may be of conventional construction, the latter having a hanger 9 provided with a hook 10 upon which the chain is adapted to be hung as illustrated.

The conductors 5 derive their support from the links of the chain, through which they pass, as already indicated, in a straight path, for which purpose each of the links is suitably formed.

A convenient form of link is constituted by bending a single piece of wire to form a plurality of portions 11 extending respectively along the axis of the chain and of the conductor thereby supported, each of these portions 11 terminating in a part 13 which

may be bent for connection with the adjacent part of the next link, as for example by means of the eyes illustrated at 13' in the respective links.

5 To co-operate with these eyes, each link has its intermediate portion bent at 14 to form a loop which extends partially or wholly around the axial path of the conductor, and is preferably bent substantially as 10 illustrated at 15 down from a transverse plane to form a sort of hook which co-operates with the eyes 13' to prevent sliding movement between the connecting portions of the links, preferably without interfering unduly 15 with a certain desirable flexibility of the chain.

The exact form of the link may be varied to meet the exigencies of particular installations, having due regard to the principal object 20 of the invention, which is to provide a path through which the connectors may be quickly inserted in a straight line, and from which the conductors may be removed with equal facility.

25 Preferably the links will be of identical formation so that the intermediate portions 14 will extend alternately toward one side and the other side of the connector, and this will serve to prevent lateral displacement of 30 the same in either direction therefrom, the straight portions 11 serving likewise to protect and give the desired direction to the conductors.

A chain thus formed constitutes an attractive, strong and serviceable support for a conductor, whether or not the latter is used for the specific purpose of supporting an electrical lighting unit of the character described, or in any position where it is desirable 35 to provide an electrical conductor with a supporting structure of the class described.

In the particular embodiment illustrated, I have shown the chain as provided with a terminal link in which the straight members 11. 45 and the intermediate portion 14 correspond with the similarly numbered parts heretofore described, so that the link may be connected readily with the other members of the chain, but the free portions of the parts 11 are bent 50 as indicated at 23 to form semi-circular attaching portions lying in a transverse plane relatively to the general axis of the chain, and adapted to be combined with the cap 16 of the connector-socket illustrated, in such a 55 manner that the latter will derive the desired support therefrom. For this purpose, the cap may conveniently have a mouth provided with a lip 17, to cooperate with the parts 23, and the connection between the cap 16 and 60 the parts 23 may be either of a permanent character or of a removable character.

This may be accomplished in various ways, viz, either by forming the cap 16 separately, so that the chain may be threaded through the mouth of the cap, until the parts 23 of 65 the terminal link engage with the bent-over lip 17, or as another mode of effecting this connection, the parts 23 may be so bent that they may be sprung toward each other and inserted through the mouth of the cap and, 70 when released, their natural resilience will cause them to spring out into position where they will be retained with sufficient strength to avoid displacement by any ordinary tension due to the weight of the lighting unit. 75

The chain and the unit connected therewith may be hung from any suitable support by hanging the upper terminal link 20 of the chain upon the supporting structure, and in the instance illustrated the upper terminal 80 link 20 is provided with a portion 22 adapted to co-operate with the hanger to which reference has already been made.

A structure thus constituted serves to support the lighting unit and the conductors 85 without any strain upon the latter.

I claim:

1. A link for a chain of the class described, said link comprising a wire having portions adapted to extend along the axis of the chain, 90 the ends of said portions being formed for connection with a connecting link, and the intermediate portion of the closed end of said link being disposed to one side of the longitudinal axis of the link to extend around an 95 electrical conductor, said closed end of the link having also spaced portions formed to be connected with the cooperating ends of another link.

2. A chain composed of links formed of a 100 single piece of wire in U shape, the free ends of the arms of the links being formed to and engaging with the closed end of the next adjacent link, the closed end of certain of the links having portions disposed to one side of 105 the longitudinal axis of the link, certain of said outwardly disposed portions being in register whereby a straight passageway for a lighting cord is provided through the chain along its longitudinal axis. 110

3. A chain composed of links formed of a single piece of wire in U shape, the free ends of the arms of the links engaging with the closed end of the next adjacent link, the closed end of certain of the links having portions disposed to opposite sides of the longitudinal axis of the chain whereby a straight passageway is provided for a lighting core through the chain along its longitudinal axis. 115

In testimony whereof, I have signed this 120 specification.

HENRY D'OLIER, JR.
